UNITED STATES PATENT OFFICE.

JOSIAH HOSKINS, OF FRENCH GULCH, CALIFORNIA.

EMERGENCY ESCAPE-WAY FOR MINES.

1,179,630.

Specification of Letters Patent. Patented Apr. 18, 1916.

Application filed June 1, 1915. Serial No. 31,615.

To all whom it may concern:

Be it known that I, JOSIAH HOSKINS, a citizen of the United States, residing at French Gulch, in the county of Shasta and State of California, have invented certain new and useful Improvements in Emergency Escape-Ways for Mines, of which the following is a specification, reference being had to the accompanying drawings.

10 This invention relates to an improved emergency escape way for mines and has for its primary object to provide a device of this character, whereby loss of life of the mine workmen, incident to disasters commonly occurring in mines, may be obviated.

15 The invention has for a more particular object to provide a device of the above character which will permit of the escape of the workmen in case of disaster, said device including a main escape shaft to which any desired number of laterally extending shafts or conduits leading into the drifts or gangways of the mine may be connected, said main escape shaft being provided with suitable doors at the various levels through which the workmen may find entrance to the interior thereof, said shaft being provided with a ladder or equivalent means for affording an easy means of ascent to the 20 ground surface.

25 It is another important object of my invention to provide means in connection with the emergency escape way for withdrawing foul air and gases from the mine so that the workmen will not be overcome thereby.

30 With the above and other objects in view, my invention consists in the novel features of construction, combination and arrangement of parts to be hereinafter more fully described, claimed, and illustrated in the accompanying drawing, in which—

35 Figure 1 is a vertical sectional view through a mine showing my improved escape way as applied in actual use; Fig. 2 is a section taken on the line 2—2 of Fig. 1; and Fig. 3 is a section taken on the line 40 3—3 of Fig. 2.

45 Referring in detail to the drawing, 5 which is constructed in a plurality of sections provided on their opposite ends with collars or flanges, indicated at 6. Suitable packing is arranged between the flanges of the adjacent pipe sections and said sections 55 are securely bolted together, as at 7, to pro-

vide hermetically sealed joints between the several sections of the shaft. The lower end of this vertical pipe or escape shaft is similarly jointed or connected to a laterally extending horizontal shaft or conduit 8. 60 By means of T or elbow joints, additional sections may be connected to this laterally extended pipe and said pipes or conduits 8 extended into every room of the mine workings, as will be readily understood. The 65 main vertical pipe or shaft 5, as well as the horizontally disposed pipes or conduits 8 are divided by the longitudinal extending walls 9 to provide the main compartments 10 therein and the relatively small compartments 11. The smaller compartments 11 of the vertically and laterally extending pipes or shafts are in communication with each other, as clearly shown in Fig. 1, to provide an unobstructed passage through 70 which foul air and gas may be drawn. For this purpose, the upper end of the compartment 11 of the vertical escape shaft 5 opens to one side of the pipe and through the same, the pipe 12 being connected which 75 extends to a suitable draft furnace. The passages 10 and 11, at the ends of the laterally disposed pipes or conduits extending into the various rooms of the mine are also open and in communication with each other, so that the foul air and gas will be drawn 80 from the mine through the passages 11 and fresh air drawn from the mine through the passages 10.

85 The vertically disposed pipe or shaft 5 is provided at the several working levels of the mine with hinged doors 13 whereby access may be had to the compartment 10 of said shaft. These doors are equipped with suitable snap fasteners or locking devices, indicated at 14, so that, after the workman 90 has entered the compartment 10, the door may be closed to securely seal the door opening and prevent the entrance of foul air or 95 gas to the shaft.

100 Bolts 15 extend diametrically through the walls of the vertical main shaft 5 and through the longitudinal bars of the ladders, indicated at 16. These ladders may 105 be made in sections of any desired length and the lower section extends downwardly into the compartment 10 of the lateral pipe or conduit 8. The opposite edges of the division wall 9, extending from the main shaft 5 in this passage of the lateral shaft, 110

are sloping or inclined, as at 17. Over the upper end of the main shaft 5 which extends above the ground surface, a suitable hood 18 is mounted so as to prevent dirt or other foreign matter dropping into said shaft and filling the lateral shaft or conduit 8 at the lower end of said main shaft.

In the accompanying drawing, I have illustrated only one of the main escape shafts 10 5; but it will be understood that any desired number of these escape shafts may be provided as the mine workings may be more or less extensive. The several pipes or conduits of the escape way are preferably constructed of heavy galvanized iron so that they will withstand the strains and pressures which may be devolved thereon. The transverse bolts 15, extending through the walls of the main shaft 5, serve to reinforce 15 the same and also provide convenient means for supporting the escape ladders in the chamber or compartments 10 of said shaft. The passage 11, through which the foul air is drawn, is closed at the upper end of the shaft 5 by means of the wall 19. The laterally extending pipe or conduit to which the vertical shaft 5 is connected, is preferably sunk below the ground level of the mine drift and covered with cement or other 30 suitable material.

In the actual use of the invention, when an explosion or other disaster occurs in the mine, the workmen therein enter the compartment 10 of the shaft 5 through the doorways provided, or enter the lateral conduits or pipes 8 extending into the several rooms of the mine, finally arriving at the lower end of one of the vertical shafts 5. The workmen then ascend the ladders in 40 the vertical shafts and thus may easily and quickly reach the ground surface. As before stated, as a forced draft is created through the several rooms or chambers of the mine and through the passages 11, accumulations of gas will be withdrawn from the mine and fresh air continuously supplied thereto, thus obviating the suffocation of the workmen before they can reach the vertical escape shafts.

From the above description, taken in connection with the accompanying drawing, the construction, manner of operation and

several advantages of my invention will be clearly and fully understood.

It will be seen that I have provided a 55 simple and highly serviceable emergency escape which is well adapted for the purpose in view.

The invention may also be installed in mines at comparatively small cost and affords a means of ready escape for miners in cases of explosion, inundations, or similar disasters in the workings of the mine.

While I have above described the preferred construction and arrangement of the 60 several features of my invention, it is to be understood that the relative arrangement of the several parts of the conduit, as well as the diameter thereof, may be varied 65 to suit existing conditions and that the invention is also susceptible of other minor modifications without departing from the 70 essential features or sacrificing any of the advantages thereof.

Having thus fully described my invention, what I desire to claim and secure by Letters Patent is:—

An emergency escape way for mines including a vertical shaft and a lateral conduit connected to the lower end of said 80 shaft, a longitudinal division wall extending through the vertical shaft and providing a gas passage and an entrance and escape passage, a longitudinal division wall extending through the conduit and providing a gas passage therein, said latter wall closing the lower end of the entrance and escape passage in the vertical shaft, said gas passages of the vertical shaft and the conduit being in communication with each 85 other, and wings projecting laterally from the opposite edges of the longitudinal division wall in the vertical shaft at its lower end to the wall of said conduit to prevent the passage of the gas from said gas passages into the entrance and escape passage 90 in the vertical shaft.

In testimony whereof I hereunto affix my signature in the presence of two witnesses.

JOSIAH HOSKINS.
